(57) **CLAIM**

The ornamental design for a "faucet," as shown.

DESCRIPTION

FIG. 1 is a generally perspective view of a faucet showing my new design;

FIG. 2 is a right end view thereof;

FIG. 3 is a left end view thereof;

FIG. 4 is a side view thereof;

FIG. 5 is a top plan view thereof; and,

FIG. 6 is a bottom plan view thereof.

The broken lines in the drawings represent portions of the faucet and form no part of the claimed design.
